CLAIM

The ornamental design for a light, as shown and described.

DESCRIPTION

FIG. 1 is a perspective view of a light;

FIG. 2 is a perspective view of a light showing power switch markings in phantom;

FIG. 3 is a plan view thereof;

FIG. 4 is a plan view thereof showing power switch markings in phantom;

FIG. 5 is a left side elevational view thereof, the right side elevational view being a mirror image thereof;

FIG. 6 is a front elevational view thereof;

FIG. 7 is a rear elevational view thereof; and,

FIG. 8 is a front elevational view thereof showing power switch markings in phantom.

The phantom lines are not part of the claimed invention.
